UNITED STATES PATENT OFFICE

169,425

HANDWHEEL OR THE LIKE

Robert F. Daehler, La Grange, Ill., assignor to
Crane Co., Chicago, Ill., a corporation of Illinois

Application July 11, 1952, Serial No. 20,570

Term of patent 14 years

(Cl. D78—1)

To all whom it may concern:

Be it known that I, Robert F. Daehler, a citizen of the United States, residing at La Grange, Illinois, in the county of Cook and State of Illinois, have invented a new, original, and ornamental Design for a Handwheel or the like, of which the following is a specification, reference being had to the accompanying drawing, forming a part thereof.

Fig. 1 is a plan view of the handwheel embodying my new design.

Fig. 2 is a sectional view taken on the line 2—2 of Fig. 1.

Fig. 3 is a sectional view taken on the line 3—3 of Fig. 1.

Fig. 4 is a sectional view taken on the line 4—4 of Fig. 1.

Fig. 5 is a sectional view taken on the line 5—5 of Fig. 1.

I claim:

The ornamental design for a handwheel or the like, substantially as shown.

ROBERT F. DAEHLER.
